Primary Examiner—Jeffrey Asch

(57) **CLAIM**

I claim the ornamental design for a key array for a handset, as shown and described.

DESCRIPTION

FIG. 1 is a right side view of the key array for a handset;

FIG. 2 is a front view thereof;

FIG. 3 is a left side view thereof;

FIG. 4 is a bottom plan view thereof; and,

FIG. 5 is a perspective front view thereof.

The portions of the drawings shown in broken lines are for illustrative purposes only and form no part of the claimed design.
